UNITED STATES PATENT OFFICE.

WILFRID M. HARRISON, OF CHESHUNT, ENGLAND.

METHOD OF AND MEANS FOR VAPORIZING FUEL FOR INTERNAL-COMBUSTION ENGINES.

1,426,187.

Specification of Letters Patent. Patented Aug. 15, 1922.

Application filed April 21, 1921. Serial No. 463,288.

To all whom it may concern:

Be it known that I, WILFRID MATTHEW HARRISON, a subject of the King of Great Britain and Ireland, residing at Cheshunt, 5 Herts, England, have invented an Improved Method of and Means for Vaporizing Fuel for Internal-Combustion Engines (for which I have filed an application in Great Britain dated April 26th, 1919, No. 10,419), of which 10 the following is a specification.

As is now well known many proposals have been made to apply heat to fuel intended to be admitted to internal combustion engines in order to enable starting to 15 be effected quickly in cold weather or in cold climates and to allow of the use of heavy cheap fuel of relatively low flash point. Of these proposals, such as make use of electrical heating means possess many points of 20 advantage although none thereof have become popular mainly because, as heretofore constituted, to be effective they are relatively costly both as regards amount of energy consumed and in construction. A convenient 25 plan is to arrange for the heating of the induction pipe or air inlet pipe but except in cases where electrical heating elements are applied not only to the induction pipe but also to other parts such as the carburettor or 30 cylinder head, which is expensive and complicated the results obtained are not satisfactory, because the known proposal of applying a removable electrical heater to pipes or connections for the purpose of heating 35 the fluid therein or passing therethrough would not be satisfactory for the purpose above referred to unless precaution be taken to prevent the cooling of the fluid after it has passed the heater, and also loss of heat 40 by radiation and convection from the exposed surface of the pipe, it not being feasible, for reasons of economy, to make the heater large enough to secure a temperature which, without this precaution, would enable 45 an engine to be readily started.

The object of the present invention therefore is to provide efficient means for the purpose referred to and it consists in the employment of an electrical heater of relatively 50 small capacity and simple construction which can be applied to any convenient part of the induction or air inlet pipe and the provision of a lagging on the remaining and exposed portion both between the heater and engine and between the heater and carburettor so that there is no detrimental cooling of the heated fuel, air or pipe.

Fig. 1 of the accompanying drawings shows in central sectional elevation one construction by way of example of apparatus 60 embodying the invention.

Fig. 2 shows the apparatus in plan.

In this construction the improved heating means are shown as applied to the induction pipe *a* but as will be understood they may 65 be similarly applied to the air inlet pipe of the carburettor instead of to the induction pipe. The heating means are constituted by a number of electrical resistance coils *b* connected at their ends to pegs *c* projecting 70 from rings *d* of earthenware, porcelain or other insulating material mounted on the induction pipe *a* the position of the lower ring *d* being determined by a split collar *e* secured to the pipe. Above the upper ring 75 *d* the pipe *a* is suitably lagged or covered with asbestos, felt or other heat insulating material *f* to prevent loss of heat by radiation. For convenience in placing the rings *d* in position on the pipe *a* each ring is preferably made in halves, hinged together at *g* and to enable the rings to fit the pipe *a* notwithstanding slight variation in size, a packing strip of asbestos or other suitable material that will yield to some extent, may be 80 placed between the meeting edges of the two parts of the ring although such a packing strip is not shown on the drawing.

The resistance coils *b* of each half ring *d* are connected in series, series parallel or in 90 parallel (according to the available electro-motive force) and to positive and negative terminals *h* and *i* respectively, and to maintain the part rings closed as well as to electrically connect the terminals of the two 95 half discs together, brass or copper hooks *j* pivoted to the terminals of the one half disc are adapted to engage the terminals of the other half discs.

The rings *d* are grooved at *k* to receive 100 the ends of a metal enclosing cylinder *l* which may also be made in two parts held together as by clip bolts *m*, and which is lined with asbestos, felt or other material *n* adapted to prevent loss of heat. Nuts *o* on 105 screws projecting from the metal enclosing cylinder *l* through holes in the rings *d* secure the parts together.

It will be understood that considerable variations in detail of construction may be 110

made without departure from the invention and that means of any appropriate type such as an electric lamp, or bell, or an indicator disc that may be coated with a luminescent substance in order to be visible at night, may be provided to indicate when the heater is in action so that waste of current may be avoided by cutting off the current so soon as the starting has been effected or when desired by means of a tumbler or other type of switch which may be placed in any convenient position in the circuit. The carrier rings *d* are not necessarily made of insulating material, indeed in many constructions it may be preferable to make them of metal and suitably to insulate the terminals and resistances as will be understood.

The necessary current may be drawn from any suitable source of electrical energy available.

What I claim is:—

1. The herein described method of supplying gaseous fluid to an internal combustion engine in heat augmented condition which consists in passing the fluid through a conduit, electrically heating the conduit, and preventing loss of heat from the fluid by radiation from the conduit after the fluid has passed the heating zone, substantially as described.

2. In an internal combustion engine, a fluid conveying pipe, an electrical heater applied thereto, and lagging between the heater and the engine whereby the radiation of heat for the pipe is reduced and the fluid after passing the heater prevented from becoming again detrimentally cooled.

3. In an internal combustion engine, an induction pipe, an electrical heater encircling a portion of such pipe and removable therefrom without having to dislodge the induction pipe, and lagging around the remainder of the pipe between the heater and the engine, for the purpose described.

4. In an internal combustion engine, a pipe encircling electrical heater, comprising a pair of diametrically divided insulating

rings mounted in separated relation, each ring having an annular groove, the groove of one facing the groove of the other, resistance coils extending between said rings, an enclosing cylinder adapted to be received in the grooves of the rings aforesaid, and means for clamping the parts together, substantially as described. 55

5. In an internal combustion engine, a pipe encircling electrical heater, comprising a pair of diametrically divided flanged insulating rings mounted in separated relation, each ring being provided with an annular groove, the groove of one facing the groove of the other, resistance coils extending between the said rings, a diametrically divided enclosing cylinder adapted to be carried in the grooves of the rings, means for clamping the parts of each ring to its corresponding part, and independent means for connecting together the thus clamped rings and cylinder parts, substantially as described. 60

6. A fuel heater for an internal combustion engine, or the like, comprising diametrically divided insulating rings adapted to be mounted upon a pipe in separated relation, a diametrically divided cylindrical casing supported between the rings, a plurality of heating elements supported between the rings and within the casing, a heat retaining element carried by the casing, and means adapted to be mounted beneath the device for supporting it in operative position. 75

7. A heater for a fuel inlet supply pipe or the like, comprising a diametrically divided cylindrical chamber supported upon diametrically divided rings, means to clamp the rings and chamber together, means to support the device upon a pipe, and a plurality of electrically heating elements within the device, for the purpose described. 85 90

Signed at 18 Cavendish Square, London, W. 1, this 6th day of April, 1921.

WILFRID M. HARRISON.
